UNITED STATES PATENT OFFICE.

FREDERICK W. ROBERTSHAW, OF PITTSBURGH, AND GEORGE A. ROBERTSHAW, OF GREENSBURG, PENNSYLVANIA.

THERMOSTAT.

Application filed September 10, 1921. Serial No. 499,599.

To all whom it may concern:

Be it known that we, FREDERICK W. ROBERTSHAW and GEORGE A. ROBERTSHAW, both citizens of the United States, residing, respectively, at Pittsburgh, Allegheny County, Pennsylvania, and Greensburg, Westmoreland County, Pennsylvania, have invented a new and useful Improvement in Thermostats, of which the following is a full, clear, and exact description.

The present invention relates broadly to thermostats, and more particularly to thermostats adapted for use in connection with ovens and the like, although its use in this respect is not limited.

An important object of the invention is to provide a thermostatically operated valve the parts of which are readily accessible for cleaning and may be removed without affecting the valve setting.

Another object of the invention is to provide a thermostat in which it is impossible to lose the original setting during ordinary use thereof.

Still another object of the invention is to provide a thermostatically operated valve having means on one end for setting the valve and means on the opposite end for correcting said setting.

A further object of the invention is to provide a device of the character described, capable of being operatively set at any desired temperature from a distance.

The foregoing and other objects of the present invention, together with their attendant advantages, will be apparent as the invention becomes better understood by reference to the accompanying specification and drawings forming a part thereof, it being premised that changes may be made in the various details and the manner of operation within the scope of the appended claims without departing from the spirit of the invention.

Figure 1 is a longitudinal sectional view through a valve and its operating thermostat constructed in accordance with the present invention;

Figure 2 is an end view of the construction illustrated in Figure 1;

Figure 3 is a top plan view of a portion of the construction illustrated in Figure 1;

Figure 4 is a detail view of the spacing and holding bracket;

Figure 5 is a view, corresponding to Fig-

ure 1, illustrating a modified form of thermostatically operated valve; and

Figure 6 is an end view of the construction illustrated in Figure 5.

Referring more particularly to the drawings, there is illustrated a supporting body which may be in the form of a valve casing 1 having an inlet connection 2 and an outlet connection 3, and constituting part of a controlling device. Intermediate the ports 60 of these connections the casing is provided with a seat 4 of any usual construction adapted to cooperate with a valve 5 for closing the connection between the inlet and outlet ports. The valve 5 is normally urged in 70 the direction of the seat 4 by a suitable spring 6, and may be guided in its movement by a stem 7 formed thereon and extending into a boss 8 projecting inwardly from the casing. Access to the casing is provided by 75 removing the closure 9, thereby permitting the parts of the valve to be removed at will for cleaning or replacing, as may be necessary. The inlet and outlet ports may be connected by a small bypass or bleed opening of usual construction, controlled by a 80 regulating screw 10, thereby permitting a pilot flame to be maintained at all times.

Extending rearwardly from the casing 2 is a projection 11 having its outer surface 85 threaded. The thread in the present construction is preferably of comparatively steep pitch and may be either a single or double thread, as desired. Cooperating therewith is a revolving couple or adapter 12 having one end threaded to cooperate with the threaded projection 11 and having its opposite end provided with a standard thread to receive the reduced threaded end 13 of the thermostat expanding element 14. 90 As is usual in constructions of this character, the member 14 may be scored or roughened over its entire surface and blackened to facilitate the absorption of heat 95 thereby.

Located within the expandable member 14 is a non-expansible member 15 of suitable material abutting against a separate pin 16 in alignment with the valve stem 7 and forming a gas tight sealed joint between the 105 valve casing and the interior of the element 14. At its opposite end the non-expansible element 15 cooperates with a screw plug 17 the purpose of which will be more fully pointed out hereinafter.

The thermostatic device is illustrated as being within an oven or similar chamber, the temperature of which it is desired to control. A portion of the oven wall 18 is 5 illustrated in the drawings.

In installing the present thermostat, it will be apparent that the gas connections determine the position of the valve casing 1. Located on the exterior of this casing so as 10 to be visible throughout its entire length to the user of the device, is a plate 19 having graduations 20 thereon which are marked to indicate different degrees of temperature at which it is desired to maintain the oven. 15 Clamped about the revolving couple 12 is an arm 21 provided with an operating handle 22 and a pointer 23 cooperating with the graduations 20 on the plate 19. By moving the handle 22 it will be apparent 20 that the revolving couple 12 is rotated, thereby moving the same toward or away from the valve casing 1 by reason of the action of the threaded projection 11. This movement is amplified by providing a thread of high 25 pitch as set forth. When the thermostatic valve is assembled, the threaded plug 17 is screwed into such a position that the operation of the valve is in accordance with the graduations on the plate 19. Thereafter, the 30 user of the valve may regulate the temperature at which the same operates by the handle 22. The plug 17 therefore provides means for correcting the setting of the valve, while the handle 22 provides means for setting 35 the same. In order to increase the range of movement of the revolving couple, to accommodate non-expansible elements of different lengths, or for other purposes, the revolving couple may have formed therein 40 two or more openings 25. Preferably two such openings are provided, positioned at diametrically opposite sides of the couple for receiving the inner end of a stud 24 carried by the bracket arm 21. This permits 45 the position of the bracket arm with respect to the couple to be changed during assembly of the valve, so that the proper reading may be obtained to within a few degrees, and thereafter the correcting plug 17 is operated 50 to produce an accurate setting.

With a construction of this kind, it will be apparent that it is impossible to lose the original setting of the valve, as the handle cannot be rotated except through a limited 55 arc determined by the connections 2 and 3. Furthermore, the setting of the thermostat is not affected by removing the valve parts as desired.

The inner end of the device may be carried 60 within a bracket 26 adapted to be secured to the oven wall or top to hold the expansible element in spaced relation thereto. This bracket will be so formed as to permit the desired rotative and longitudinal movement 65 of the expansible member.

In Figures 5 and 6, there is illustrated a construction generally similar to that before described, and the parts corresponding to parts already referred to are designated by the same reference character with a prime 70 affixed thereto. In this form of the invention, the valve casing is illustrated as having its inlet and outlet connections 2' and 3' at diametrically opposite sides thereof. It will be apparent, however, that the arrangement of these connections is immaterial. In this construction, the valve casing 1' is provided with an index pointer 23' and the revolving couple 12' carries a pulley 27 secured thereto by a stud 24' and provided with graduations 20' cooperating with the pointer 23'. Around the periphery of the pulley is passed a flexible operating cable 28 the opposite ends of which may carry suitable weights or handles 29 enabling the pulley 27 to be rotated to set the temperature at which the valve operates, as will be apparent.

Both forms of the invention illustrated provide a construction in which there is a 90 correcting device located at one end of the thermostatic valve and a setting device located at the opposite end thereof, the setting and correcting devices being capable of independent manipulation as required. 95

The advantages of the present invention arise from the construction of the valve and its controlling thermostat in such manner that the valve parts may be removed at will without affecting the setting of the thermo- 100 stat.

Other advantages of the invention arise from the couple provided between a body carrying the member to be acutated, or the controlling device, and the thermostat. 105

Further advantages arise from the provision of setting and correcting devices permitting an accurate operation of the thermostat at all times.

Still further advantages arise from the 110 provision of a construction in which the operating temperatures are visible to the user of the device, and in which the original setting of the thermostat cannot be lost during the use thereof.

We claim:

1. A thermostat, comprising a supporting body, a member movably mounted thereon, an expansible member, a revolving couple connecting said body and said member, and a non-expansible member cooperating with said expansible member for operating the member on said body, substantially as described. 120

2. A thermostat, comprising a controlling 125 device having a movable operating member, an expansible member, a revolving couple connecting one end of said expansible member and said device, a correcting device at the opposite end of said member, and a non- 130

expansible member cooperating therewith for operating the movable member of the controlling device, substantially as described.

5 3. A thermostat, comprising a controlling device having a movable operating member, a threaded projection on said device, the threads on said projection having a high pitch, a revolving couple cooperating with 10 said projection, an expansible member carried by said couple, a non-expansible element cooperating therewith for operating the movable member of said device, and means for revolving said couple to vary the 15 temperature at which the device is operated, substantially as described.

4. A thermostat, comprising a valve casing having inlet and outlet openings, a valve controlling communication between said 20 openings, a threaded projection on said casing, the threads on said projection having a high pitch, a revolving couple in threaded engagement with said projection, a tubular expansible member carried by said 25 couple, a correcting device cooperating with one end of said member, a non-expansible member within said first mentioned member and abutting against said correcting device and said valve for operating the valve, 30 and means for revolving said couple to change the temperature at which the valve is operated, substantially as described.

5. A thermostat, comprising a tubular expansible member, a non-expansible member 35 located therein, a correcting device at one end of said expansible member for engagement with said non-expansible member, a valve operatively secured to the opposite end of said expansible member for cooperation with said non-expansible element, and means independent of said correcting device 40 for changing the adjustment between said valve and said non-expansible member, substantially as described.

45 6. A thermostat, comprising a valve casing having inlet and outlet openings, a valve controlling communication between said openings, an expansible member, a revolving couple connecting said casing and said member, a non-expansible member cooperating with said expansible member for operating the valve, and means permitting removal of said valve without affecting the setting of the thermostat, substantially as 50 described.

55 7. A thermostat, comprising a casing having inlet and outlet connections, a removable valve controlling communication between said connections, a removable closure in said 60 casing providing access to said valve, an expansible member, a revolving couple connecting said casing and said member, and a non-expansible member cooperating with said expansible member for operating the 65 valve, substantially as described.

8. A thermostat comprising a controlling device having a movable operating member, an expansible member, a revolving couple connecting said device and said expansible member, a non-expansible member cooperating 70 with said expansible member for operating said device, means for revolving said couple for varying the temperature at which said device is operated, and means for indicating the temperature for which the device 75 is set, substantially as described.

9. A thermostat, comprising a valve casing having inlet and outlet connections, a valve controlling communication between said connections, a threaded projection on said casing, a revolving couple cooperating with said threaded projection, an expansible member carried by said couple, a non-expansible element cooperating therewith for operating said valve, and means for revolving 80 said couple to vary the temperature at which the valve is operated, substantially as described. 85

10. A thermostat, comprising a valve casing having inlet and outlet openings, a valve controlling communication between said 90 openings, a threaded projection on said casing, a revolving couple in threaded engagement with said projection, a tubular expansible member carried by said couple, a correcting device cooperating with one end of said member, a non-expansible member within said first mentioned member and abutting against said correcting device and said valve for operating the valve, and 95 means for revolving said couple to change the temperature at which the valve is operated, substantially as described.

11. A thermostat, comprising a controlling device having a movable operating member, an expansible member, a revolving couple connecting said device and said expansible member, a non-expansible member, and a separate longitudinally movable pin intermediate said non-expansible member and said device, substantially as described. 105

12. A thermostat, comprising a casing having inlet and outlet connections, a valve controlling communication between said connections, an expansible member, a revolving couple connecting one end of said member and said casing, a correcting device at the opposite end of said member, a non-expansible member, and a separate packing pin intermediate said non-expansible member and 110 the valve, substantially as described. 115

13. A thermostat, comprising a valve casing having inlet and outlet connections, a valve controlling communication between said connections, a threaded projection on said casing, a revolving couple cooperating with said projection, an expansible member carried by said couple, a non-expansible member cooperating therewith, a separate packing pin intermediate said non-expans- 125 130

- ble member and the valve, and means for revolving said couple to vary the temperature at which the valve is operated, substantially as described.
5. 14. A thermostat, comprising a valve casing having inlet and outlet openings, a valve controlling communication between said openings, an expansible member, a revolving couple connecting said casing and said member, a non-expansible member, a separate packing pin intermediate said non-expansible member and the valve, and means permitting removal of said valve without affecting the setting of the thermostat, substantially as described.
10. 15. A thermostat, comprising a casing having inlet and outlet connections, a removable valve controlling communication between said connections, a removable closure 20 in said casing providing access to said valve, an expansible member, a revolving couple
- connecting said casing and said member, a non-expansible member, and a separate packing pin intermediate said non-expansible member and the valve, substantially as described. 25
16. A thermostat, comprising a controlling device having a movable operating member, an expansible member, a revolving couple connecting said device and said expansible member, a non-expansible member co-operating with said expansible member for operating the movable member of said device, and means permitting removal of the movable member of said device without 30 affecting the setting of the thermostat, substantially as described. 35

In testimony whereof we have hereunto set our hands.

FREDERICK W. ROBERTSHAW.
GEORGE A. ROBERTSHAW.
